(57) **CLAIM**

The ornamental design for a footwear sole component, as shown and described.

DESCRIPTION

FIG. 1 is a perspective view of a footwear sole component embodying the new design;

FIG. 2 is a top view thereof;

FIG. 3 is a right side view thereof;

FIG. 4 is a left side view thereof;

FIG. 5 is a front view thereof; and,

FIG. 6 is a rear view thereof.

FIGS. 1–6 show portions of an article of footwear in short dash-short dash-long dash broken lines. The portions illustrated in short dash-short dash-long dash broken lines are shown for environmental purposes and form no part of the claimed design. Further, the short dash-short dash-long dash broken lines immediately adjacent the solid-line portions of the design form the boundary of the design, with the broken lines forming no part of the claimed design. The heavy dash-dash broken lines represent a line of stitching, which does form a part of the claimed design.
